ABSTRACT

A method of forming an exterior corner bend in fibrous sheet material in which a pair of parallel, overlapping, V-shaped grooves are formed across one side surface of the material so as to provide a pair of bevelled edge faces spaced apart by a triangular rib, filling the V-shaped grooves with a liquid settable rib and maintaining the sheet in its bent condition until the adhesive sets.

Fig. 3

CORNER BEND IN FIBROUS SHEET MATERIAL

BACKGROUND OF THE INVENTION

1. Field of the Invention

This invention relates to forming exterior bends in fibrous sheet material, such as plywood sheeting, for finishing trim around doorways, window casements and the like.

2. Prior Art

Conventionally, trim around doorways and the like, has usually been made of finished dimensioned lumber which is stained or otherwise finished to match the wall panelling or door adjacent. With modern prefinished door skins in which the finished side can be a suitable plastic such as vinyl or paper which can be treated to simulate any type of wood it is very difficult, if not impossible, to obtain and finish solid wooden trim to obtain an exact match. Consequently doorway trim and the like, is now, in many cases, formed substrate material as the door and which has an exterior finish which matches, exactly, the finish of the door.

Individual members of the latter type of trim have a channel cross-section and are formed from a single finished piece of substrate which is suitably corner bent and glued to provide the required strength.

In prior art procedures for forming a corner bend a V-shaped groove is cut in the unfinished side of the piece through the various substrate thicknesses up to but not through the exterior finish. The groove is then filled with a suitable adhesive then bent to the desired angle along the V-shaped groove and held in position until the adhesive has set. The exterior corner bend thus formed usually presents an unbroken exterior finish, if the finish is vinyl. With exterior finishes of a fibrous nature such as paper, splitting of the finish sometimes occurs.

Furthermore an exterior corner as formed above presents a sharp edge which is susceptible to damage and cannot easily be repaired.

SUMMARY OF THE INVENTION

The present invention provides a method for forming corner bends in sheet material of a rigid fibrous nature which provides a chamfered exterior corner and which is, consequently, not as readily damaged as sharp cornered corner bends.

Furthermore, the present method of forming corner bends reduces incidences of splitting of the exterior finish particularly where the finish material is of a fibrous nature, such as paper.

In accordance with the invention the corner bend is formed by cutting two parallel, over-lapping, V-shaped grooves across the unfinished side of the panel up to but not through the exterior finish so as to form a central triangular rib, filling the grooves with a suitable adhesive then bending the panel on lines coincident with the bottoms of the V-shaped grooves, and maintaining the bend until the adhesive has set.

A detailed description following, related to drawings, gives exemplification of methods according to the invention which, however, is capable of expression in method other than those particularly described and illustrated.

DESCRIPTION OF THE DRAWINGS

FIG. 1 is a sectional view of a door jamb, trim members of which are formed in accordance with the invention.

FIG. 2 is an enlarged sectional view of a portion of a trim member prior to bending.

FIG. 3 is a sectional view illustrating a finished corner bend.

DETAILED DESCRIPTION

Referring to the drawings, FIG. 1 is a transverse section of one side of a door jamb having a stop 10, jamb faces 11 and 12, and side trim 13 and 14 all of which are formed of thin plywood sheeting finished on one side which is corner bent to provide an unbroken finished surface.

The corner bends of the door stop and jamb faces are 90° in extent, whereas, trim 13 and 14 have corner bends 15 and 16, less than 90° and corner bends 17 and 18 which are greater than 90°. The exterior corner bends are all formed in the same manner.

Referring to FIGS. 2 and 3 which show a typical corner bend and a method of making the same, the numeral 21 designates a sheet of laminate fibrous material, for example plywood, which has an unfinished interior surface 22 and has a finishing veneer 23 applied, in a known manner, to its outer surface 24. The finish, can, conventionally be vinyl or paper or other known materials.

A pair of parallel, over-lapping, V-shaped grooves 25 and 26 are formed across the interior surface 22, the apices 27-27 extending to, but not through, the exterior finish 23 so as to form a central triangularly shaped rib of wood 29 and a pair of panels 31 and 32 which have bevelled edge faces 33 and 34 and which are connected only by the exterior finishing veneer 23. The rib, for plywood one-eighth inches in thickness, suitably, a base length of one-sixteenth inches.

The V-shaped grooves are then filled with a suitable liquid adhesive 35, for example a hot melt glue having a polyethylene or polyester base, and the panels are then folded around fold lines represented by the apices 27-27 of the grooves and maintained in a folded condition until the glue has set.

The apex angle and spacing of the V-shaped groove is such that when the panels 31 and 32 are bent to the desired angle, see FIG. 3, the panels meet at the junction of the bevelled end faces and the inside surfaces of the panel. It will be seen that during bending the volume of the V-shaped grooves is reduced so that ideally excess glue is squeezed out onto the inside surface of the panels. This strengthens the exterior corner bend thus formed.

The provision of the central rib results in a chamfer 31 rather than a sharp corner edge — the deflection angle at each edge of the chamfer being only one half of the corner bend angle. Due to the decreased deflection angle and due to the softening of the veneer by the hot glue, incidences of splitting of the finishing veneer, at the corner bend during production, is markedly reduced.

Furthermore the chamfered corner can withstand, without excessive damage, the impact of hard objects.

It is to be understood that although reference has been made to corner bending fibrous material having exterior finishing veneer the same method of corner

bending can be used with plywood sheets having no finishing veneer. In this case depth of the V-shaped grooves is only slightly less, approximately 8/1000 inches, than the thickness of the sheet material.

I claim:

1. An exterior corner structure for a rigid sheet of fibrous material having a flexible sheet of finishing veneer on the exterior surface thereof comprising:

- a. a pair of sheet portions connected by said veneer extending unbroken between the two sheet portions,
- b. said sheet portions being at substantially a right angle to each other,
- c. said sheet portions having bevelled end faces,
- d. a central rib of triangular cross-section disposed between said end faces and connected to said ve-

neer and having side surfaces spaced from said bevelled end faces,

e. the inner edges of said sheet portions being in contact with each other and said end faces being non-parallel to each other whereby a space is defined by said end faces of said sheet portions and said side surfaces of said central rib, and

f. an adhesive substantially filling said space and bonded to said end faces and said side surfaces.

2. A corner bend as claimed in claim 1 in which the adhesive is a hot melt glue.

3. A corner bend as claimed in claim 1 in which the triangularly shaped rib has a base length of substantially one-sixteenth inches.
